STEAM INJECTOR FOR INTERNAL-COMBUSTION ENGINES

Eugene Drydyke, Milwaukee, Wis.

Application November 2, 1950, Serial No. 193,605

4 Claims. (Cl. 123—25)

This invention relates to steam injectors for internal combustion engines.

It is well known that combustion in internal combustion engines may be materially improved by the addition of small amounts of vapor or steam to the gaseous fuel mixture. Such additions in proper proportions and under proper conditions impart a desirable anti-knock quality to the fuel and tend to avoid and to eliminate objectionable carbon deposits within the engine.

Many devices have been proposed for this purpose but, as heretofore designed, none have proven entirely satisfactory and none are in general use. Many such devices are too complicated and expensive to justify their existence and many are incapable of properly proportioning the added steam under various conditions of engine operation. Inability to supply adequate quantities of steam renders such devices ineffective, while additions of steam in excessive amounts, or containing appreciable amounts of free water, impairs combustion and results in ill effects on the engine.

One object of the present invention is to provide a steam injector capable of introducing into the fuel mixture properly proportioned quantities of water-free steam under various conditions of engine operation. This I have accomplished by providing a steam reservoir in which is maintained an adequate supply of water-free steam at substantially constant pressure, preferably atmospheric pressure, and from which the steam is led and directed into the engine intake manifold through a nozzle projecting thereinto, the flow through the latter being induced by the suction or sub-atmospheric pressure within the manifold and being controlled largely by the size of the nozzle discharge orifice. Provision is also preferably made to automatically compensate at least in part for the varying conditions that normally occur within the intake manifold under various conditions of engine operation.

Other more specific objects and advantages will appear, expressed or implied, from the following description of a steam injector constructed in accordance with the present invention.

An illustrative embodiment of the present invention is shown in the single figure of the accompanying drawing.

The steam injector shown includes a suitable boiler 10 formed by a jacket 11 welded to and encircling a portion of the exhaust pipe or manifold 12 of an internal combustion engine. Water is supplied to the boiler 10 preferably from a supply tank 13 through suitable tube or pipe connections 14 and 15 and an interposed float valve 16.

The float valve functions to maintain the water in the boiler 10 at a substantially constant level, such that the boiler is about one quarter full. Although this valve may assume various forms, in this instance it comprises a closed housing 16, having a top vent 17, and connected to the bottom of the boiler 10 through the connection 15. The connection 14 from the supply tank 13 leads to a fitting 18 in the top of the housing 16 containing a needle valve 19 that controls admission of water to the latter. The needle valve 19 is shown loosely seated in a depression 20 formed in the upper end of a suitable float 21 which is loosely guided by bails 22 for free vertical movement within the housing 16. Lack of a positive connection between the valve 19 and float 21 assures a free action of the valve in the fitting 18, this condition being further enhanced by the lubricating effect of water contained in the depression 20. It will of course be understood that the valve 19 is opened by the pressure of the supply water and

controlled by the rise and fall of the float 21 in the housing 16.

A suitable connection 23 provides communication between the upper end of the boiler 10 and a steam reservoir 24. The reservoir shown comprises a substantially cylindrical housing, preferably slightly tilted, and equipped at its lower end with a drain orifice 25 for the escape of water of condensation. The connection 23 is preferably arranged to admit steam from the boiler 10 to the lower end of the reservoir.

The capacity of the boiler 10 is such as to maintain the reservoir 24 filled with steam under all operating conditions, and the latter is preferably vented so as to maintain the contained steam at approximately atmospheric pressure. In this instance venting is effected by a tube 26 projecting through the top of the reservoir and covered by an open-sided hood 27 preferably filled with a suitable filter material such as steel wool, glass wool or the like.

A steam conductor tube 28 leads from the upper end 20 of the reservoir 24 to a discharge nozzle 29 arranged to direct the steam into the fuel mixture passing through the intake manifold 30 of the engine. The nozzle 29 is shown mounted in and projecting through the side of the manifold and terminating in a restricted orifice 31 disposed substantially centrally of the latter, so as to effect an intimate mixture of the discharged steam with the passing fuel mixture.

The fuel conductor tube 28 is preferably of a size to provide unrestricted flow of steam to the nozzle 29, this flow being induced by the suction or sub-atmospheric pressure within the manifold, and the rate of flow being governed largely by the size of the nozzle orifice 31. To compensate for the wide variations in manifold suction resulting from changes in engine throttle positions, provision is made for automatically regulating the rate of admission of steam from the reservoir 24 to the steam conductor tube 28. For this purpose the reservoir shown is equipped with a butterfly valve 32.

In this instance the valve 32 is rockably supported within the reservoir 24 and so arranged that when closed, it separates the upper end from the remainder of the reservoir. It is yieldably urged toward closed position by a suitable spring 33, that being the position assumed when the engine is idling at closed throttle position, and in that position little or no steam enters the fuel mixture. Valve 32 is controlled by a lever arm 34 connected through appropriate linkage 35 to the control lever 36 of the engine throttle, one end of the link 35 being engaged in a short slot 37 provided in the lever 36, so as to provide a lost-motion connection therebetween. The arrangement is such that as the throttle lever 36 is swung toward the left from the closed-throttle position shown, the slot 37 permits the valve 32 to remain in closed position until the throttle has been moved from an idling position to a running position, and thereafter the valve 32 opens to an extent substantially corresponding to that of the throttle.

For the purpose of conserving steam and the supply water, provision is preferably made for withdrawing excess steam from the boiler 10, condensing the same, and returning the water of condensation to the boiler. In this instance a hollow fitting 38 containing a suitable hand controlled valve 39 is attached to the boiler, well above the water level therein, and steam escaping through the valve is conducted through a tube 40 to a suitable condenser 41, the water of condensation being returned to the boiler through a tube 42 communicating with the water supply connection 15. Water of condensation escaping from the steam reservoir 24 through the drain orifice 25 is also returned to the boiler through a connection 43 between the orifice and the tube 40. The fitting 38 is preferably disposed well below the connection 23 in order that it may serve to carry away any water-laden bubbles that normally rise above the water in the boiler, to thereby intercept and prevent entry of such bubbles into the steam reservoir 24 through that connection 23.

From the foregoing it will be noted that a steam reservoir 24 has been provided which is maintained filled with steam at substantially atmospheric pressure; that the reservoir steam is devoid of free water, since it is supplied from the top of a boiler in which the water is maintained at a low level, and since any water of condensation oc-

curing in the reservoir is promptly discharged through the drain port 25; that the tube 28 provides a clear and ample passage for the steam from the reservoir 24 to the discharge nozzle 29 free from any possible obstruction by water of condensation or otherwise; and that the steam, thus delivered to the nozzle, is directed through the nozzle orifice 31 into the passing fuel mixture at a point to insure an intimate mixing therewith and at a rate determined largely by the size of the orifice. It will be further noted that the valve 32 contained within the reservoir 24 functions automatically to cut off the supply of steam to the tube 28 and nozzle, when the engine is idling, and when the suction in the manifold is at a maximum, and to progressively clear the path of steam flow to the tube and nozzle as the engine throttle is opened and the suction in the manifold correspondingly reduced.

Various changes may be made in the embodiment of the invention hereinabove specifically described without departing from or sacrificing the advantages of the invention as defined in the appended claims.

I claim:

1. A steam injector for use in conjunction with an internal combustion engine including a throttle control, said injector comprising a steam reservoir including venting means for maintaining the same at atmospheric pressure, a steam boiler operatively associated with the exhaust pipe of the engine and connected to said reservoir to supply the same with live steam, connecting means associated with said reservoir and the intake manifold of the engine to deliver steam from said reservoir to the intake manifold, a valve disposed in said reservoir for controlling the release of steam from said reservoir to said intake manifold, yieldable means for normally maintaining said valve in closed position, and an operating means associated with said valve and the throttle control, said last named means being responsive to movement of the throttle control to regulate the admission of steam from said reservoir to the intake manifold.

2. A steam injector for use in conjunction with an internal combustion engine including a throttle control, said injector comprising a steam reservoir including venting means for maintaining the same at atmospheric pressure, a steam boiler operatively associated with the exhaust pipe of the engine and connected to said reservoir to supply the same with live steam, connecting means associated with said reservoir and the intake manifold of the engine to deliver steam from said reservoir to the intake manifold, a valve disposed in said reservoir for controlling the release of steam from said reservoir to said intake manifold, yieldable means for normally maintaining said valve in closed position, and operating means including a lost-motion disposed between said valve and the throttle control, said operating means being responsive to movement of the throttle control to regulate the operation of said valve and said lost-motion connection providing the means whereby the opening of said valve in response to movement of said throttle control is delayed to preclude the admission of steam to the intake manifold until the speed of the engine exceeds its normal idling speed.

3. A steam injector for use in conjunction with an internal combustion engine including a throttle control, said injector comprising a steam reservoir including venting means for maintaining the same at substantial atmospheric pressure, a steam boiler operatively associated with the exhaust pipe of the engine and connected to said reservoir to supply the same with live steam, connecting means associated with said reservoir and the intake manifold of the engine to deliver steam from said reservoir to the intake manifold, a valve disposed in said reservoir for controlling the release of steam from said reservoir to the intake manifold, yieldable means for normally maintaining said valve in closed position, operating means associated with said valve and throttle control and responsive to movement of the throttle control to regulate the admission of steam from said reservoir to the intake manifold, means for maintaining a substantially constant liquid level in said boiler, and a condenser operatively associated with said steam boiler for receiving and condensing the excess of steam generated by said boiler over the amount required to maintain said reservoir filled.

4. A steam injector for use in conjunction with an internal combustion engine including a throttle control, said injector comprising a steam reservoir including venting means for maintaining the same at substantial atmospheric pressure, a steam boiler operatively associated with the exhaust pipe of the engine and connected to said reservoir to supply the same with live steam, connecting means associated with said reservoir and the intake manifold of the engine to deliver steam from said reservoir to the intake manifold, a valve disposed in said reservoir for controlling the release of steam from said reservoir to said intake manifold, yieldable means for normally maintaining said valve in closed position, operating means including a lost-motion disposed between said valve and the throttle control, said operating means being responsive to movement of the throttle control to regulate the operation of said valve and said lost-motion connection providing the means whereby the opening of said valve in response to movement of said throttle control is delayed to preclude the admission of steam to the intake manifold until the speed of the engine exceeds its normal idling speed, and a condenser operatively associated with said steam boiler for receiving and condensing the excess of steam generated by said boiler over the amount required to maintain said reservoir filled.
